UNITED STATES PATENT OFFICE.

JESSE ALEXANDER, OF NEW YORK, N. Y., ASSIGNOR OF ONE-HALF TO R. F. COCHRANE,
OF MOUNT VERNON, NEW YORK, AND ONE-HALF TO HERBERT W. LITTLE, OF NEW
YORK, N. Y.

TYPE-WRITING-MACHINE ACTION.

1,077,112.

Specification of Letters Patent.

Patented Oct. 28, 1913.

Continuation of application Serial No. 468,425, filed December 21, 1908. This application filed November 4, 1912. Serial No. 729,326.

To all whom it may concern:

Be it known that I, JESSE ALEXANDER, a citizen of the United States of America, and residing at New York, in the county of 5 Kings and State of New York, have invented new and useful Improvements in Type-Writing-Machine Actions, of which the following is a specification.

My invention relates particularly to type- 10 writer actions for machines of the front stroke visible writing type.

The main object is to provide a simple construction having a quick and powerful printing action and a quick return move- 15 ment.

The invention contemplates the use of units each of which comprises a hinged key lever and a hinged type bar and a hinged sub lever or intermediate lever connecting 20 the key lever and the type bar. The sub lever has a pin and slot connection with the key lever and three points of connection with the type bar. One of these points of connection serves to start the type bar to- 25 ward the printing position. Another effects the relative movement between the sub lever and the type bar at a point intermediate the beginning and end of the stroke. The third serves to assist in the first part 30 of the return movement of the type bar.

Figure 1, is a side view and vertical section showing one unit of the action in its normal position of rest. Fig. 2, is a detail side view of one of the type bars. Fig. 3, 35 is a side view and vertical elevation showing one of the units in the printing position. Fig. 4, is a side view of one of the sub levers.

The key lever 1 is hinged at 2 and may be 40 under the lifting tension of the spring 3. The universal bar 4 extends beneath the key levers and is connected by a link 5 to the escapement rocker 6 which is under tension of the adjustable spring 7. The platen 8 45 is carried by a carriage construction movable transversely of the machine under the control of the escapement rocker.

The type bar 10 has a hook 11 hinged 50 on the pivot rod 12 in the type bar segment 3. The front ends of the type bars rest on the bracket 14.

Each intermediate lever or sub lever 15 is

hinged on the pivot 16 and has a slot 17 to receive the pin 18, carried by the key lever 1.

Each type bar has a pin 19 normally engaged by the front edge of its sub lever. Each sub lever has a slot in its upper end with a shoulder 20 at its rear for the pin 21 carried by the type bar. The slot has a 60 downward extension 22 to facilitate assembling and dismounting the parts. The type bar also has a shoulder 23 which is brought adjacent the pin 24 carried by the sub lever when the parts are in the printing position 65 of Fig. 3.

When a key lever is depressed it rocks its sub lever forward about its pivot 16 and by its engagement with the pin 19 starts the type bar toward the printing position. As 70 the type bar rises, the pin 21 swings downward and forward and is engaged by the shoulder 20 which forces the type bar to the printing position. When the key lever is released it is raised and the sub lever is 75 rocked to the rear. The pin 24 pushing against the shoulder 23 throws the type bar forward quickly so as to avoid conflicting with the other type bars.

What I claim is:-

1. In a typewriter action, a hinged type bar having a downward projection to be engaged by a sub lever edge at the beginning of the printing stroke, a sub lever for engagement therewith, said type bar and said 85 sub lever having a pin and slot connection for quick action at an intermediate part of the stroke and a pin and shoulder engagement at the end of the printing stroke to facilitate the return of the type bar. 90

2. In a typewriter action, a hinged type bar having a pin below and at some distance from its pivot and a second pin below and in rear of its pivot when the type bar is in the normal position of rest and a sub lever normally engaging the first pin and having an elongated slot with a shoulder at the front end thereof for engagement with the second pin in the normal position of rest and a shoulder at the rear end thereof for co-acting with the second pin during the intermediate part of the printing stroke, said sub lever and said type bar having other parts which coact at the printing position. 100

3. In a typewriter action, a hinged type bar having a pin and a shoulder, a hinged sub lever having its front edge normally engaging said pin and carrying a pin adapted to be engaged by said shoulder at the printing position.
4. In a typewriter action, a hinged type bar having a pin and a shoulder, a hinged sub lever having a slot for engaging said 10 pin and having a pin adapted to be engaged by said shoulder at the printing position.
5. In a typewriter action, a hinged type bar, and a hinged sub lever engaging directly with the type bar and having three 15 points of connection with said type bar op-

erating at the beginning, the intermediate part and the end of the stroke.

6. In a typewriter action, a hinged type bar having two pins at different distances from the pivot of the type bar and a 20 shoulder at an intermediate distance from the pivot of said type bar and a hinged sub lever having shoulders for engaging said pins and a pin for engagement with the shoulder of said type bar.

JESSE ALEXANDER.
